(57) **CLAIM**

The ornamental design for a backhoe, as shown and described.

DESCRIPTION

FIG. 1 is front view of a backhoe showing our new design;

FIG. 2 is a rear view thereof;

FIG. 3 is a left side view thereof;

FIG. 4 is a right side view thereof;

FIG. 5 is a top view thereof;

FIG. 6 is an upper left front perspective view thereof;

FIG. 7 is an upper left rear perspective view thereof;

FIG. 8 is an enlarged upper left front perspective view of a portion thereof; and,

FIG. 9 is an enlarged upper left rear perspective view of a portion thereof.

A bottom view is omitted because it is plain and unornamental and forms no part of the subject matter of the claimed design.

The portions of the backhoe shown in broken lines form no part of the claimed design.
